UNITED STATES PATENT OFFICE.

MICHAEL KENNEDY, OF WASHINGTON HEIGHTS, ILLINOIS.

ICE-BOX.

SPECIFICATION forming part of Letters Patent No. 248,475, dated October 18, 1881.

Application filed May 4, 1881. (No model.)

To all whom it may concern:

Be it known that I, MICHAEL KENNEDY, of Washington Heights, in the county of Cook and State of Illinois, have invented certain new and useful Improvements in Ice-Boxes, of which the following is a specification.

My invention relates to improvements in ice-boxes; and it consists in making the walls of the ice-box of cement, supported on and strengthened by wire-cloth; and it also consists in the novel features of construction herein described.

In the accompanying drawings, which form a part of this specification, and in which similar letters of reference indicate like parts, Figure 1 is a perspective view of a device embodying my invention. Fig. 2 is an enlarged vertical section on the line *y y* of Fig. 1.

The box is constructed with a frame, A, of wood or metal, coated so as to be non-conducting, and the walls, the top, and the bottom are composed of cement, B, or similar plastic non-conducting material, laid upon a course or courses of wire-cloth, C, stretched between and secured to the timbers of the frame. The panels of cement between the timbers may be made flush with the timbers, or so as to present a slightly-recessed appearance.

I prefer to divide my ice-box into compartments, one of which, D, is used to hold the ice, and the others, E, are made to serve as receptacles for the food products. The former is made with a self-draining floor, *d*, also of cement and wire-cloth, with an opening, *d'*, through which the meltings and condensation of moisture may drip into a pan, *d''*, located below, and from which they may be drawn off through an outlet-pipe, *d'''*. The exterior walls of the box are made double—that is, with two courses of cement laid upon wire-cloth—with an air-space, F, between them, and the vertical partition-walls D', dividing the ice-chamber from the rest of the box, are similarly constructed.

G G are openings in the partition-walls D', through which the cold from the ice-chamber

may be communicated to the food-chamber. Similar openings may be made in the inner half of the exterior wall of the chamber into the space F, and other openings from the latter into the food-chamber, whereby additional channels of communication between the ice and floor chambers are provided and circulation is insured.

The doors are constructed of the same materials as the walls of the box. The wire-cloth may be secured to the frame in any suitable way. By grooving the frame and inserting the edges of the cloth therein, the edges are covered and strength is obtained. The wire-cloth and cement stiffen the frame and render the box firm and unyielding. The pan *d''* serves to cool in some measure the provision-chamber.

My improved ice-box is not expensive to make, is very economical of ice, and very efficient in operation.

I am aware that ornaments for walls and ceilings of buildings have been made with wood frames having wire-netting stretched thereon and plaster or stucco laid upon or applied to the netting; also, that slabs have been made of a plastic non-conducting material having wire-cloth embedded therein, and that such slabs have been used in and upon walls, floors, roofs, and ceilings of buildings where a fire-proof material was desired; and hence I do not claim the construction of the walls of my improved ice-box independently of the box.

I claim—

1. The ice-box consisting of the frame A and walls of cement and wire-cloth, substantially as specified.
2. The ice-box the walls whereof are made of cement laid upon and supported by wire-cloth, substantially as specified.

MICHAEL KENNEDY.

Witnesses:

H. M. MUNDAY,
EDMUND ADCOCK.
